HOSE CLAMP

Nils Seaholm, Mount Vernon, N. Y., assignor to
Carroll W. Prochaska, Tuckahoe, N. Y.

Application October 2, 1943, Serial No. 504,686

1 Claim. (Cl. 24—19)

This invention relates to clamping devices for auto hose, sand blast hose and the like and has for its particular objects the provision of a rugged, readily adjustable clamp of that character which may be conveniently applied and removed from a hose without disturbing the position of the latter. Further objects of the invention are the provision of a clamp construction which is extremely cheap to manufacture, compact and attractive in appearance. Other objects of the invention will hereinafter appear.

In the accompanying drawing, in which I have illustrated certain preferred forms of the invention,

Figure 1 is a side elevation and Figure 2 an end elevation of a clamp embodying one form of the invention;

Figure 3 is an enlarged fragmentary, central, vertical section, taken on the line 3—3 of Figure 2, the same being partly broken away;

Figure 4 is a transverse section, taken on the line 4—4 of Figure 3;

Figure 5 is an enlarged fragmentary, vertical section, taken along the longitudinal axis of the lower portion of the clamp shown in Figure 1; and

Figure 6 is a perspective view of a modified form of worm shaft, isolated.

Referring to the drawing and the construction shown therein, the reference numeral 10 designates generally the band member of the clamp, the same being formed of two halves or elements 11 and 12 that are hinged together in the manner hereinafter explained. The lower end *a* of the element 11 is folded on itself to reinforce the same and the folded portions are apertured, as indicated by the reference letter *b*, and are rigidly secured together by a rivet *c*. The lower end of the element 12 is also folded on itself to form an eye *d* which is inserted through the aperture *b* and these latter folded portions are rigidly secured together by a rivet *e*.

The elements 11 and 12 are respectively cut away to form longitudinal slots 13 and 13' and thereby reduce the weight thereof without objectionably weakening the same. The band element 11 is also provided with a series of parallel, slightly oblique slots 14 which are tapered at their respective ends as designated by the reference letter *x* and which slots serve to engage a worm element hereinafter described.

The upper end *f* of the element 12 is also folded on itself to reinforce the same and to form a stop element to prevent the escape thereover of a housing member 15 that is rigidly secured by

5 rivets *g*, *g'* to the element 12 immediately beyond the folded area thereof. Said housing has opposing circular terminal apertures 16 and 16', opposing slots 17 and 17' and inturned lower ends or feet 18 and 18' whose adjacent faces abut each other.

10 A worm shaft 20 is journalled in the housing 15, the same projecting through the said terminal apertures 16, 16' thereof. An annular shoulder 21 which is formed on said shaft adjacent the reduced or flattened end 22 thereof functions, in 15 co-operation with the adjacent lateral wall of the housing, as a thrust bearing for said shaft. A worm sleeve 23, which is of a size to snugly fit on said shaft between the lateral walls of the housing, is rigidly splined to said shaft by a pin or spline element 24 which projects through said sleeve and said shaft and has a snug fit therewith.

20 In Figure 6, the shaft 25 shown therein has an enlarged end or head 26 which is provided with a terminal slot 27 for the reception of a screw driver and said shaft is adapted to be substituted, if desired, for the shaft shown in Figures 1-3 25 which latter has a flattened end for the reception of a wrench.

25 The free end of the element 11 is desirably cut off to an oblique edge *y* to facilitate its entrance into the slots 17 of the housing when applying the clamp to a hose or the like and admit 30 of the free rotation of the worm when such oblique edge engages the same and thereafter of the successive entry of the worm into each of the adjoining slots on said element 11.

35 My improved clamp due to its unique construction is remarkably strong, being capable of resisting without breakage or distortion of the housing a pressure exerted on said shaft by means of a socket wrench or screw-driver of several hundred pounds. This is of the utmost importance 40 in the automotive and many heavy industries employing water cooled gasoline engines, especially since such clamps are often required to withstand on test a minimum applied pressure of 180 pounds.

45 The construction of the band element with two plies, integrally united together, at the end thereof to which the housing member 15 is riveted results in the edge of the lower ply or fold *f* functioning as a remarkably effective stop to insure that the housing cannot escape over the adjacent end of the band element since the rear end of the foot 18 will, when high pressure is applied to the worm 23, be incapable of movement longitudinally of the band member even were the

rivets g, g' to become sheared off under the applied high pressure. Also, due to the fact that the opposed inturned feet which form the bottom of the housing 15 abut on a line transversely of the longitudinal axis of the band member, the housing can neither collapse nor spread under such pressure. These features of my improved clamp are of the utmost importance and are by no means merely a difference in degree as the mere use of heavier material in the different elements of the clamp would not accomplish the same purpose and would for many uses be too cumbersome and expensive.

Various modifications of the foregoing construction within the scope of the appended claim may be made without departing from the spirit of my invention.

Having thus described my invention, what I claim is:

A clamp having a band member consisting of 20

5 a single ply of metal throughout the principal portion of its length that is folded on itself immediately adjacent one end thereof to form two plies, the lower one of said plies having an edge that extends transversely of the longitudinal axis of the band member and which serves as an abutment, a housing member formed of a single sheet of metal rigidly secured to said band member and whose lower edge abuts against said lower ply edge, said housing member having opposing end walls each provided with an aperture for the reception of a worm shaft and also each provided with a transverse bottom slot for the reception of two plies of the band member when the same are in overlapped relation on each other and said housing member having opposing feet elements, integral therewith, whose free ends abut each other and which elements constitute the bottom of said housing member.

NILS SEAHOLM.
